INVENTOR.

Frederick Stearn

United States Patent Office.

FREDERICK STEARNS, OF DETROIT, MICHIGAN.

Design No. 2,928, dated February 4, 1808.

DESIGN FOR A BOTTLE.

The Schedule referred to in these Letters Patent and making part of the same.

TO ALL WHOM IT MAY CONCERN:

Be it known that I, FREDERICK STEARNS, of Detroit, in the county of Wayne, and State of Michigan, have originated and designed a new Form of Bottle for containing coco-oleine, of which the following is a full, clear, and exact description, reference being had to the accompanying drawings, making a part of this specification, and in which—

Figures 1 and 2 are perspective views, each from different points, and
Figure 3 is a plan view of the bottom.

The nature of this invention consists in manufacturing a glass bottle, A, of any required size, the front thereof being nearly double the width of the sides, and the front and rear sides thereof provided with indented panels, B, while the corners, C, are fluted or concave, as shown in the drawings. Upon one end, D, I cause to be blown the words "Fred'k Stearns," and upon the opposite end, E, I also cause to be blown the compound word "Coco-oleine." The neck F is blown in the usual form.

What I claim as my invention, and desire to secure by Letters Patent, is—

The design of the bottle, with the words blown into its ends, as herein set forth and shown.

F. STEARNS.
